UNITED STATES PATENT OFFICE

ROY CHADWICK, OF NEWTON HEATH, MANCHESTER, ENGLAND, ASSIGNOR OF ONE-HALF TO A. V. ROE & COMPANY LIMITED, OF NEWTON HEATH, MANCHESTER, ENGLAND, A BRITISH COMPANY

MACHINE GUN MOUNTING

Application filed October 6, 1930, Serial No. 486,820, and in Great Britain November 5, 1930.

This invention relates to the mountings for machine guns of the type in which the gun is carried by a frame of substantially U shape pivotally attached to a ring running upon a circular runway, the invention being particularly applicable to gun mountings for aeroplanes, airships, tanks, warships, anti-aircraft guns, motor boats and other like services.

10 The object of the present invention is to provide improved means for controlling the catches by which the frame is held in any desired position with relation to the ring and the latter is secured to the runway.

15 The invention comprises, in machine gun mountings of the type specified, the arrangement of the control means for the catches by which the frame is locked to the ring and the latter to the runway, through a hollow spindle forming the pivot of the frame upon the ring.

20 The invention further comprises the arrangement of conical members upon a spring loaded rod passing through the hollow spindle about which the frame pivots, and plunger-like parts engaging said cones and operating the catches as the rod is moved longitudinally through the hollow spindle.

25 Referring to the two accompanying sheets of explanatory drawings:—

Figure 1 is a plan view partly in section and Figure 2 a side elevation, also partly in section, of a gun mounting with locking means constructed and arranged in one convenient form in accordance with my invention for use for example upon an aeroplane.

30 Figure 3 is a side elevation, also partly in section, of the opposite side of the mounting to that shown in Figure 2.

35 The same reference letters in the different views indicate the same parts.

The gun is mounted in the usual swivel fittings permitting of universal movements of the gun, and such fittings are carried at a in the U shaped frame b which is pivotally mounted at its ends about a hollow spindle c carried in brackets d secured to the ring e which can be turned upon the circular runway f. Secured to each bracket d are two toothed or notched quadrants g, one at each

side of the pivotal end of the frame b, the teeth or notches in which are adapted to be engaged by keys h, one guided in each end of the frame b and loaded by a spring i. Each key is adapted to be moved clear of the said teeth or notches against the pressure of its spring i by a plunger like member j having at one end a roller k engaged by a conical member m upon a tubular rod n extending from side to side of the frame b and through which passes a cable o connected at one end to the threaded member p upon the end of the rod n and at the other end to a hand lever q. An arm r is pivotally connected to the rod n as shown in Figure 3 and serves to turn a spindle s which operates a spring loaded locking-bolt t adapted to enter any one of the series of holes in the runway f in order to hold the ring e in any desired position upon the runway.

35 The adjustment or setting of the cones m which release the keys h and the arm r which releases the locking bolt t is such that the keys are moved clear of the quadrants g before the ring e is released from connection with the runway f by the bolt t, so that the frame b can be moved about its axis before the ring e is freed for circular movement.

40 Torsion springs u coiled around the spindle c are each connected at one end to a collar v upon such spindle and at the other end to the fixed brackets d or parts attached thereto. As the frame b turns with the spindle c to which its ends are connected by keys w, the action of the springs u is to tend to 45 turn the frame to an upright position. A series of holes may be provided in the collar v and the ends of the springs u may be passed into any one of the said holes to give the desired torsional power to the springs.

45 My improved catch operating means are simple and effective, and can be readily adjusted by means of the threaded member p in the end of the rod n where it is accessible for manipulation to set the parts accurately 50 and to compensate for any stretch of the cable o.

What I claim is:—

55 1. Machine gun mounting comprising in combination, a circular runway, a ring run-

ning upon said runway, a gun carrying frame of substantially U shape pivotally attached to said ring, a hollow spindle extending across the open end of said carrying frame and about which the latter pivots, an inner member extending across the two branches of the carrying frame within the said hollow spindle, and manually controlled means for moving said inner member to operate simultaneously locking devices provided within both arms of the U shaped carrying frame thereby freeing said frame, the said movement of the inner member also operating an additional locking device on one side 15 of the ring whereby the latter is free to rotate on its runway.

2. Machine gun mounting comprising in combination, a circular runway, a ring running upon said runway, a gun carrying frame 20 of substantially U shape pivotally attached to said ring, notched quadrants fixed upon the ring and disposed concentrically with the axis of movement of the frame, spring loaded catches within each branch of the frame 25 adapted to engage said quadrants, conical members upon a spring loaded rod passing through a hollow spindle about which the frame pivots, plunger like parts engaging said cones and operating the catches as the 30 rod is moved longitudinally through the hollow spindle, a hand grip for operating said rod pivoted upon the frame and connected to one end of a cable, and the other end of which is connected to said rod, and a bolt for locking the ring to its runway also operated from 35 said rod.

3. Machine gun mounting as claimed in claim 2 in which the cable passes through the spring loaded rod from end to end there- 40 of and is secured thereto at the far end of the rod by an adjustable screw threaded member.

4. Machine gun mounting as claimed in claim 2 in which the bolt for locking the ring to its runway is raised or lowered by an arm 45 operated by the spring loaded rod, the said bolt passing through the said ring into any one of a series of holes in the runway.

In testimony whereof I have signed my name to this specification.

50 ROY CHADWICK.
